UNITED STATES PATENT OFFICE.

WESLEY WEBBER, OF PITTSBURG, PENNSYLVANIA.

DEEP-WELL-DRILLING APPARATUS.

SPECIFICATION forming part of Letters Patent No. 471,580, dated March 29, 1892.

Application filed January 14, 1891. Serial No. 377,710. (No model.)

To all whom it may concern:

Be it known that I, WESLEY WEBBER, of Pittsburgh, in the county of Allegheny and State of Pennsylvania, have invented a new and useful Improvement in Deep-Well-Drilling Apparatus, of which the following is a full, clear, and exact description, reference being had to the accompanying drawings, forming part of this specification, in which—

10 Figure 1 is a side elevation of my apparatus, part of the case being broken away for clearness of illustration. Fig. 2 is a vertical central section of part of the apparatus. Fig. 3 is a similar section of part of the apparatus, showing the drill mechanism in different positions. Fig. 4 is a horizontal section on the line IV IV of Fig. 2. Fig. 5 is a horizontal section on the line V V of Fig. 2. Fig. 6 is a detail view of a part. Fig. 7 is a side view of the parts of the apparatus in working position, and Fig. 8 is a front view of the winding-drum. Fig. 9 is a detail view of the bull-wheel and connections, and Fig. 10 is a detail view of the gudgeon and connections.

25 Like symbols of reference indicate like parts in each.

My invention is an improvement on the well-drilling apparatus for which I have obtained United States Letters Patent No. 30 431,131, dated July 1, 1890, and an improvement also on the apparatus for which on October 24, 1890, I filed an application for United States Letters Patent, Serial No. 369,183.

The object of the invention is to provide 35 improved means by which electricity can be used to furnish the motive power for deep-well drilling.

The advantages derived from use of my improved apparatus are that the work of drilling is expedited and cheapened, and, because the apparatus used is very unlikely to become lodged in the hole, fishing jobs, which are a cause of great delay and expense in well-drilling, are rendered to a great extent 45 unnecessary.

In the drawings, 2 represents a case, preferably of cylindrical form and of proper size to admit its insertion into the well to be drilled. Within this case are electric motors 50 3, preferably two or more, which may be arranged in the manner ordinarily employed in similar connections. In Fig. 1 I show only

one of these motors, which is sufficient to illustrate the principle of my invention, which relates principally to the construction of the 55 mechanism by which power is transmitted to the drilling-bit and to the construction of the bit itself. The armature of the motor is contained within the magnet, and a shaft 4 is journaled in bearings in the case and is fixed 60 to the armature and is rotated thereby. The shaft is interrupted at 5 by a piece or joint of insulating material.

66 are the electrical conductors connected with the magnet and of sufficient length to 65 extend from the top to the bottom of the well to be drilled. In the use of the apparatus these conductors are connected to a suitable generator of electricity situated at the surface of the ground, the cable containing the conductor being led within the center of the winding-drum shaft 42 and there contacting 70 with a post 43, which protrudes beyond the shaft and is provided with a collar upon which contact-brushes 44 rest, and thereby 75 communicate the current to the cable, all as shown in Fig. 8.

The ordinary derrick 45 is used in operating my device, the cable passing over the crown-pulley and thence to the drum 46. 80

The motor is held in position in the case by insulated supporting plates or brackets.

On the shaft 4 is a gear-wheel 7, which by means of other gear-wheels 8, constructed as shown, actuates a crank 9, which may be on 85 the shaft of the last gear-wheel of the series.

10 is a rod which connects the crank with a link 11. A rod 12 passes through an eye at the lower end of the link and is provided with collars 13 and 14, arranged as shown. A 90 spring 15 is interposed between these collars, and the lower end of the link has an intermediate bearing on the spring.

16 17 are guide-bearings through which the rod 12 passes.

18 is a plate or partition which closes the case 2 above the crank 9 to prevent access of water from below into the part of the case containing the electric motor. The shaft 4 passes through and has a bearing in this plate. 95

The drilling-bit is secured to the lower end of the rod 12 and is preferably constituted of two blades 19, pivoted to the rod at their upper ends by a pin 20 and provided with toggle-

arms 21, so that when they are drawn up within the case, as shown in Fig. 2, they shall be drawn together into small lateral compass, and so that when projected, as shown in Fig. 5 3, they shall diverge. The toggle-arms 21 are pivotally connected at their outer ends to lugs on a ring 22, which is rotatory within the case, being supported and confined by annular shoulders or flanges 23 therein.

10 When the electric current is supplied by the conductors 6, the rotation of the armature is communicated by the shaft 4 to the gearing 7 8, and by the crank 9 a reciprocation is imparted to the rod 10 and link 11, which, acting 15 through the spring, imparts a reciprocating motion to the rod 12. The spring prevents the mechanism from acting with injurious shocks and jars which might otherwise interfere with its work. Obviously the projecting 20 of the rod 12 will by the toggle-arms cause the blades of the bit to spread, as shown in Fig. 3, while the upward stroke of the rod will bring them together, as in Fig. 2.

When the apparatus is to be used for drilling, it is let into the well by a cable, which at 25 the surface of the ground is preferably provided with a temper-screw, by which it may be lowered gradually.

In Fig. 2 the line *b b* represents the bottom 30 of the hole. On the downward stroke of the rod 2 the blades 19 engage the earth at *b b* and cut it, and by the toggle-arms 21 they are caused to act outwardly as well as downwardly and to cut a hole wider than the case 2.

35 When the bit strikes the earth, it penetrates it somewhat, and then the further motion of the crank 9 on the downstroke is taken up by compression of the spring 15. At each stroke of the bit the earth is cut 40 away a little more deeply and the spring permits the tool to descend correspondingly. When the bit finally descends to the limit of the throw of the crank, a projection 24 on the rod 12 comes into contact with a trigger 25, 45 to which is attached a contact rod or button 26, which is drawn thereby into contact with the terminals 27 of electrical conductors 28, which extend to the surface of the well and are there in circuit with an electric bell or 50 other signal, as shown in Figs. 9 and 10. In these figures 47 represents the one wire connected to the gudgeon or post 43, and 48 the insulated signal-wire passing through the gudgeon and having contact-brushes 49, which

55 bear upon the stationary rings 50 and 51, to which the electric circuit 52 is connected. In this circuit is provided a source of electrical energy 53 and a signal 54, which is operated as above described to warn the driller when 60 to lower the cable. On the sounding of this signal the driller feeds down on the suspending cable, thereby lowering the case 2 deeper into the well, so that the bit may again begin cutting. This relieves pressure on the trigger 25, which is raised by a spring 29, so 65 as to break the circuit and stop the sounding of the alarm. The operation is thus con-

tinued as long as necessary to complete the drilling of the well. From time to time the case 2 may be withdrawn and the sand bailed 70 out, or the sand may be removed by a pump, as described in my application, Serial No. 377,709, filed January 14, 1891, concurrently herewith.

In order to steady the case 2 during the 75 drilling operation, I may provide it with laterally-projecting wheels 30, held by spring-bearings and adapted to bite into the sides of the well.

It is desirable that during the drilling operation the bit should be rotated, so as to cut in all directions. For this purpose I provide the surface of the ring 22 with ratchet-teeth, as shown in Fig. 6, and use a pawl 31, pivoted to the case at 32, and connected by a rod 33 to an eccentric 34 on the shaft of the crank 9. Reciprocation of the rod 33, caused by operation of the eccentric, oscillates the pawl 31, which, acting on the ratchet-teeth, causes the ring 22 to turn and by means of the toggle-arms 21 to turn the drilling bit and rod 12. The end of the pawl 31 is provided with a spring 35 to enable it to clear the ratchet-teeth on its back-stroke.

For the purpose of preventing access of 95 water to the motors I prefer to provide the case 2 with a small pump-cylinder 36, having an inlet-port 37 communicating with the interior of the case above the partition 18 and having an outlet-port 38, which may communicate with the case below said partition. The plunger 39 of this pump-cylinder is provided with a suitable valve and is actuated by a jointed rod 40 from a crank-pin 41 on a driven gear-wheel 8'. This pump will discharge any water and sediment which may leak into the upper part of the case. It is described and claimed in said patent-application, Serial No. 377,709, filed by me on January 14, 1891, and is not claimed herein. 105 110 115 120 125

The advantages appertaining to my improvement have been indicated generally above and will be appreciated by those skilled in the art.

Without limiting myself precisely to the 115 described construction and arrangement of the parts, which may be varied by the mechanician, I claim as new—

1. In a deep-well-drilling tool, the combination of an electric motor, a drilling-bit having 120 downwardly-moving divergent parts pivoted in the case, and crank connections between the motor and bit for reciprocating the bit and opening the ports, substantially as and for the purposes described.

2. In a deep-well-drilling tool, the combination of a case containing a motor, a drilling-bit composed of downwardly-moving divergent parts reciprocated thereby, and toggle-arms connecting the movable parts and the 130 interior of the case, substantially as and for the purposes described.

3. In a deep well-drilling tool, the combination of a drilling-bit composed of downwardly-

moving diverging parts, means for reciprocating and rotating the bit, and levers adapted to be actuated by such reciprocation to depress and open the parts of the bit, substantially as described.

4. In a deep-well-drilling tool, the combination of a case containing an electric motor, a reciprocating drilling-bit operated thereby and having diverging parts, means for diverging the parts as the bit is projected, and a spring through which the reciprocating motion is transmitted to the bit, substantially as and for the purposes described.

5. In a deep-well-drilling tool, the combination of an electric motor, a drilling-bit, crank connections between the motor and bit for reciprocating the latter, a ratchet and pawl connected with the motor and adapted to rotate the bit, and a case containing the several parts, substantially as and for the purposes described.

6. In a deep-well-drilling tool, the combination of a case containing an electric motor, a drilling-bit connected therewith and adapted to be projected thereby, and an electric signal constructed and arranged to be operated at the limit of the projection of the bit, substantially as and for the purposes described.

7. In a deep-well-drilling tool, the combination of a case containing an electric motor, a reciprocating drilling-bit operated thereby, a spring through which reciprocating motion is imparted to the bit, and an electric signal constructed and arranged to be operated by the bit at the limit of its projection, substantially as and for the purposes described.

8. In a deep-well-drilling tool, the combination of a case containing an electric motor, a drilling-bit connected therewith and operated thereby, and projecting guide-wheels connected with the case and having spring-bearings, substantially as and for the purposes described.

9. In oil-well-operating machinery, the com-

bination, with the derrick and crown-wheel, 45 of a cable passing thereover, said cable being provided with wires which contact with the gudgeon of the bull-wheel, a brush bearing on said gudgeon, and a source of electrical energy connected with said brush, substantially as 50 and for the purposes described.

10. In oil-well-operating machinery, the combination, with the derrick and crown-wheel, of a cable passing thereover, said cable being provided with separate insulated 55 wires, one set of wires connecting at the bull-wheel with a source of electrical energy and the other set connecting with an electric signal-circuit, substantially as and for the purposes described.

11. In oil-well-operating machinery, the combination, with the derrick and crown-wheel, of a cable passing thereover, said cable being provided with separate insulated wires, a bull-wheel provided with a hollow gudgeon, and brushes bearing upon the gudgeon and connected with a source of electrical energy, one set of wires connecting with said gudgeon and the other set passing therethrough and connecting with an electric signal-circuit, substantially as and for the purposes described.

12. In a deep-well-drilling tool, the combination of a case containing an electric motor, a reciprocating drilling-bit operated thereby, 75 an electric signal-circuit having a circuit-closer within the case, a tongue upon said circuit-closer, and a projection upon the bit, arranged to engage said tongue at the limit of the projection of the bit, substantially as and 80 for the purposes described.

In testimony whereof I have hereunto set my hand this 8th day of January, A. D. 1891.

WESLEY WEBBER.
